UNITED STATES PATENT OFFICE

WILLIAM H. JOHNSON, OF ARTESIA, TERRITORY OF NEW MEXICO.

INK-WELL.

1,001,276.

Specification of Letters Patent. Patented Aug. 22, 1911.

Application filed March 15, 1911. Serial No. 614,748.

To all whom it may concern:

Be it known that I, WILLIAM H. JOHNSON, a citizen of the United States, residing at Artesia, county of Eddy, and Territory of 5 New Mexico, have invented certain new and useful Improvements in Ink-Wells, of which the following is a specification.

This invention relates to ink wells.

The present invention has for its object 10 the provision of a simple, inexpensive, neat, strong, and durable holder for ordinary ink bottles or wells which is adapted for quick and easy attachment to any style of school or other desk or table and which will prevent 15 the ink from spilling or the ink well or holder from becoming loosened.

The invention embodies a novel holder, part of which is adapted to be attached to the desk or table and the other part to be 20 movably carry or hold the ink well or bottle and which is adapted for attachment to the part on the desk or table, as will appear more fully hereinafter.

In the accompanying drawings: Figure 1 25 is a front perspective view showing the invention in position on a school desk; Fig. 2, a vertical section of the same; and Fig. 3, a detail perspective of the carrier and ink bottle detached.

30 A part of an ordinary school desk is shown at 1, as provided with an opening 2 which receives a screw-threaded sleeve 3 having a flange 4 adapted to overlap the desk and provided with a suitable pivoted cover 5.

35 The holder or carrier 6 may be of sheet or cast metal and is preferably of open box-like form having a screw-threaded collar 7 adapted to be screwed into the sleeve 3 and to receive the neck or mouth 8 of the ink well or 40 bottle 9 which latter may be any ordinary commercial ink bottle. The ink bottle is

supported and held in tightly clamped position by a follower 10 on a screw-threaded stem 11 which engages a screw-threaded part 12 of the holder and is provided with 45 a suitable thumb-piece or head by which it may be turned.

The complete carrier or holder can be unscrewed from the sleeve 3 and, with the ink bottle, removed from the desk then taken 50 out by unscrewing the follower. Another ink bottle may then be substituted and the carrier and ink bottle screwed into the sleeve 3. The clamping action caused by screwing the collar into the sleeve holds the flange of 55 the sleeve on the desk or table.

I wish it understood that various modifications could be resorted to in carrying out the invention, that it is adapted to hold any kind of an ink well or bottle, and that a 60 different form of connection between the ink carrier and the sleeve could be employed, all without departing from the spirit and scope of the invention.

Having thus described my invention, what 65 I claim as new and desire to secure by Letters Patent, is:

In an ink well, the combination with a desk or table, of an ink bottle carrier having a collar adapted to receive the neck of an 70 ink bottle, a releasable clamp for holding the ink bottle on the carrier with its neck in the collar, said carrier and ink bottle being adapted to be moved as a unit, and a screw sleeve for detachably securing the ink bottle carrier to the desk or table. 75

In testimony whereof, I hereunto affix my signature in presence of two witnesses.

WILLIAM H. JOHNSON.
